UNITED STATES PATENT OFFICE.

CHARLES DAVID CHASE, OF SAN FRANCISCO, CALIFORNIA, AND EDMUND PEARSON DOLE, OF HONOLULU, TERRITORY OF HAWAII.

NON-REFILLABLE BOTTLE.

SPECIFICATION forming part of Letters Patent No. 756,584, dated April 5, 1904.

Application filed June 11, 1903. Serial No. 161,010. (No model.)

To all whom it may concern:

Be it known that we, CHARLES DAVID CHASE, residing at San Francisco, in the county of San Francisco and State of California, and EDMUND PEARSON DOLE, residing at Honolulu, in the Island of Oahu and Territory of Hawaii, citizens of the United States, have invented certain new and useful Improvements in Non-Refillable Bottles; and we do hereby declare the following to be a full, clear, and exact description of the invention, such as will enable others skilled in the art to which it appertains to make and use the same.

Our invention relates to certain new and useful improvements in bottles of that class known as "non-refillable bottles," and which have for their purpose to prevent the fraudulent refilling of a bottle after its original contents have been withdrawn. Many attempts have been made to accomplish the purpose named and many devices having that end in view have been constructed; but so far as we are aware none of such devices have proven successful for the reason that they either are not practical under all circumstances or become inoperative and inefficient by reason of complex and expensive construction and the tending to soon get out of adjustment.

Our invention has for its object to provide simple and economic means which shall automatically prevent the refilling of a bottle or other containing vessel after its original contents have been withdrawn and which shall be effective for its purpose under any and all conditions.

With these ends in view our invention consists in the peculiar construction and arrangement hereinafter more fully explained.

In order that those skilled in the art to which our invention appertains may know how to make and use the same and fully appreciate its operation and advantages, we will proceed to describe our improvement, referring by letters to the accompanying drawings, in which—

Figure 1 represents a central vertical section of the neck and a portion of the breast of a bottle with our improvements in proper position to prevent the fraudulent refilling of

the bottle. Fig. 2 represents in perspective the several parts constituting the controller removed from the neck of the bottle. Fig. 3 represents a section similar to Fig. 1 and with the bottle in position to permit the escape of its contents, the controller-valve and tubular receptacle being of modified construction to that shown at Figs. 1 and 2; and Fig. 4 is a perspective view of the modified valve and tubular seat removed from the neck of the bottle.

Similar letters of reference denote like parts in the several figures of the drawings.

A represents a bottle or other receptacle, within the neck or exit portion of which is formed an annular groove B or two oppositely disposed recesses adapted to receive and interlock with the ends of a U-shaped device C for securing a guard to the controller devices in proper relation with the bottle. The device C is located within a wire cage D, and the spring ends of the device C pass through diametric orifices E near the upper end of the wall of the cage and are adapted to spring into the annular groove or recesses B, and the cage D, thus located and locked in position, constitutes a guard against any fraudulent manipulation of the controller devices located below the same.

The neck of the bottle A is formed with an enlarged chamber G, which is separated from the main chamber or body of the bottle by a floor or partition H, with an axial channel or passage adapted to receive a tubular valve-receptacle I, at the lower end of which is formed an annular interior flange J to constitute a seat for the lower end of a reciprocating valve, to be presently explained. The lower portion of this tubular valve-receptacle I is provided exteriorly with a thin cork tube K, adapted to make a liquid-tight joint between the tube I and the surrounding surface of the floor H in order that the contents of the bottle may not leak into the chamber G. While we have described and prefer this cork tube for making a tight joint, any other suitable material may be used.

The tubular valve-receptacle I is formed with any desired number of peripheral open-

ings L, constituting liquid-passages leading to the chamber G of the bottle. These passages terminate at the upper end at a predetermined locality, so as to leave a continuous tubular or ring portion M of sufficient proportions and strength to preserve the cylindrical contour of the structure and to make a closure with the neck of the bottle at its juncture with the chamber G through the medium of a cork or other packing-ring located between the ring portion M and the neck of the bottle, or the neck of the bottle may be so proportioned as to make a close joint with the valve-receptacle and the packing thus rendered unnecessary. The circumferential openings or passages L terminate at their lower extremities, so as to leave a continuous closed cylindrical portion N sufficiently high to constitute a perfect guard for the lower end of the reciprocating valve and to prevent the passage of the liquid contents of the bottle to the chamber G until the valve has moved a desired or predetermined distance.

O is a tubular valve of substantially the same construction as the tubular receptacle I and likewise having peripheral passages P and solid or ring portions Q and a closed bottom R. This valve O is adapted to fit within the tubular receptacle I and its closed bottom to be seated upon the interior flange J thereof. Both the valve O and its tubular receptacle I are so constructed as described that they shall have ample stability to preserve their forms, while also permitting the freest possible flow of the contents of the bottle through the passages L and P, as will be presently explained, and at the same time presenting a minimum of frictional surfaces between the two devices. To avoid the possibility of undue adhesion between the closed bottom of the valve O and the flange J of the tube I when the parts become wet, the said flange I is made as narrow as possible consistent with constituting a substantial seat for the valve.

When the several parts are assembled and arranged as shown at Fig. 1, the tube I will be in liquid-tight contact at its upper and lower extremities with the terminus of the neck proper of the bottle and the side wall of the axial orifice in the floor H, respectively, and will thus be protected against longitudinal movement, which is supplemented, in so far as the upward movement thereof is concerned, by the presence of the gauze-wire cage D, the bottom of which is, as shown, in contact with the upper extremity of the tube I, and as the U-shaped device C securely locks the cage in position the latter tends to hold the tube I in its fixed position and also in an obvious manner guards the entrance from without to the tube I, and consequently protects the valve O, which is located within the tube, against fraudulent manipulation. This cage also subserves the purpose of limiting the outward movement of the valve and also

closes any space between the upper end of the tube I and wall of the neck of the bottle to such an extent as to cause the concentration of any inward flow of liquid directly upon the valve and closes or seats the same instantly. 70

If desired, any space existing between the tube I and the wall of the neck-orifice may be closed and a tight joint secured in the same manner that a tight joint is secured between the lower end of the tube I and the wall of the 75 axial opening of the floor H.

The wire cage D is for convenience of manipulation made in two parts, as shown at Fig. 2, the top body integral and a cup-shaped bottom portion adapted to rest upon the upper end of the tube I. When the cage is in position, it cannot be removed without manipulating or destroying it, and hence such condition would clearly indicate that the valve devices had been tampered with and the 80 integrity of the contents of the bottle destroyed. 85

In the modification illustrated at Figs. 3 and 4 the valve O is shown with the bottom open and the top R' closed, which is the reverse of the construction shown at Figs. 1 and 2, and the tubular valve-receptacle I is shown with its lower closed portion N of greater extent in order that communication between the interior of the body of the bottle and the chamber G cannot occur until the openings L and 90 P in the tube I and valve O come into proper register by the reciprocating movement of the valve, said movement in the upward or outward direction being in this case limited by a cross-bar S, arranged in the tube I. 95

Having described the construction and arrangement of the several parts, we will now describe the operation of the same. As clearly shown at Fig. 1, and assuming the bottle to be empty or partially so, communication between the chamber G and the interior of the body of the bottle is effectually closed by the presence and position of the valve O, and an attempt to introduce liquid of any kind into the bottle through the neck-passage will obviously load 100 the valve and cause it to effectually maintain its seat within the tube I, thus preventing the flow or passage of the fluid to the interior of the bottle. If the bottle be turned into the emptying position, (shown at Fig. 3,) liquid obviously could only be passed into the neck of the bottle under pressure or by submerging the bottle in the same, and in either case the pressure of the liquid upon the light and easily-reciprocating valve O would cause the 105 same to move upward and in close contact with its seat J, thus effectually closing communication between the chamber G and the interior of the bottle. In other words, the reciprocating valve O is, in so far as its action 110 is concerned, a float-valve and sensitive to such a degree that it necessarily moves in the direction of the flow of the liquid it is designed to regulate. When the bottle is caused to assume the position shown at Fig. 3, and as 115

suming that it is wholly or partially filled, the gravity of the fluid will cause the valve O to reciprocate to the position shown, in which position it has traveled outwardly from its seat upon the flange J of the tube I, and the passages or openings P in the periphery or side wall have been brought into register with the similar passages or openings L of the tube I, so that the contents of the bottle are free to flow in the direction of the arrow below the closed bottom or top, as the case may be, of the valve and into the chamber G, and from said chamber, as indicated by the second arrow, through the registered opening of the valve O and tube I into the neck of the bottle and through the wire cage D to the exit.

The drawings accompanying this specification are made upon a scale representing an ordinary full quart-bottle, and the controller devices are shown as made upon a corresponding scale. The inside diameter of the neck of the bottle is preferably made slightly greater than the diameter of the valve-seat tube I and the axial passage through the partition or floor H in order to facilitate the introduction and proper location of the tube I.

Many slight variations in the details of construction and arrangement of the several parts may be made for the convenience or economy of manufacture without departing from the spirit of our invention. For instance, in lieu of using cork or similar substances to constitute a packing and to make a tight joint between the tube I and the surfaces of glass with which it contacts the glass may be suitably ground to produce what is commonly known as a "ground joint."

When the bottle or similar receptacle is designed to contain slow-flowing liquids, it may be desirable to increase the diameter of the neck of the bottle and the capacity of the chamber G, and when it is designed to contain liquids of a somewhat sticky nature, such as Worcestershire sauce or wines rich in sugar, a cross-bar or radial pin may be substituted for the continuous annular flange J, in order to decrease the area of contact between the valve and its seat.

Having described the construction and operation of our improved bottle, what we claim as new, and desire to secure by Letters Patent, is—

1. In combination with a bottle having a chamber at and below the lower terminus of the neck-orifice and of a diameter greater than the same and with a partition or floor between the enlarged chamber and the interior space of the bottle and provided with an axial orifice

or passage; a tube open at both ends and provided with peripheral openings or passages and seated at each end within the orifice in the neck and the axial passage of the floor or partition respectively; a reciprocating valve located within the tube and having peripheral passages adapted to register with the like passages in the tube and having one end closed; a valve-seat at or near the bottom of the tube to support the valve; means for limiting the movement of the valve away from its seat, and means within the neck of the bottle to guard the valve against fraudulent manipulation, substantially as hereinbefore set forth.

2. In a bottle such as described, and having an enlarged chamber at the terminus of the orifice in the neck, and a partition or floor with an axial passage therein between the enlarged chamber and the interior space of the bottle; a valve tube or receptacle sealed liquid-tight at its lower end within the axial passage of the floor or partition and extending to and within the lower extremity of the orifice or passage in the neck of the bottle, and having peripheral openings or passages extending above the plane of the floor; a reciprocating valve mounted upon a seat within the containing-tube and having one end closed and peripheral passages or openings; a wire cage located within the neck of the bottle and above the valve-containing tube, and a spring-bar located within the wire cage and having its free ends extending through the cage and seated in a groove or recesses in the neck of the bottle, substantially as and for the purpose set forth.

3. In a bottle such as described, and provided with the chamber G, tube I, and valve O, the tube I provided at or near its lower end with an internal seat for the valve, and means for limiting the movement of the valve away from its seat, substantially as hereinbefore set forth.

4. In a bottle such as described, and provided with the annular groove or recesses B within the neck and provided with devices between the neck and breast for controlling the flow of liquid from or into the bottle, the two-part wire cage and the U-shaped device C, substantially as and for the purposes set forth.

In testimony whereof we affix our signatures in presence of two witnesses.
